Primary Examiner — Kevin K Rudzinski*Assistant Examiner* — Clare Ann Gannon(74) *Attorney, Agent, or Firm* — Schwabe, Williamson & Wyatt, P.C.(57) **CLAIM**

I claim the ornamental design for a shoe, as shown and described.

DESCRIPTION

FIG. 1 is a front perspective view of a shoe, showing my new design;

FIG. 2 is a right side view thereof;

FIG. 3 is a front view thereof; and,

FIG. 4 is a top view thereof.

The dot-dash broken lines represent boundaries of the claimed design and form no part of the claimed design. The broken lines depicting the remainder of the shoe show features that form no part of the claimed design.
